assignors, by mesne assignments, to Automatic
Electric Laboratories, Inc., a corporation of
Delaware

Application September 18, 1943, Serial No. 502,884
In Great Britain October 15, 1942

7 Claims. (Cl. 179—27)

1

The present invention relates to telephone or like signaling systems and is more particularly concerned with the setting and control of automatic telephone switching apparatus over long trunk routes involving mixed systems of voice frequency and direct current dialling and supervision. The long trunk routes envisaged may include thermionic repeaters and echo suppressors and the invention is therefore particularly applicable to the method of V. F. signaling described in our application Ser. No. 489,136, filed May 31, 1943, now Patent No. 2,376,352, dated May 22, 1945.

According to this method of V. F. signaling, the numerical direct current impulses received at the sending end of the trunk are converted into voice frequency coded signals which are transmitted over the trunk and re-converted at the terminal end into numerical direct current impulses. Furthermore, each voice frequency coded signal is preceded by a prefix signal which is the same for all codes and serves the purpose of testing the incoming equipment and also switching any echo suppressor in the route into the correct direction of transmission preparatory to the sending of the coded signal which is characteristic of the D. C. train of impulses to be transmitted.

This method of signaling gives a good degree of speech immunity in that by reason of their length and combination the signals used rarely if ever occur in speech. In fact the degree of immunity against false operation is so good with this method of signaling that the use of so-called stopper valves which have hitherto been generally used in V. F. systems to prevent the extension of disturbing signals forwardly over the trunk are no longer considered necessary and have not been provided. Previously such stopper valves were included in the apparatus at the sending end of the trunk line and served to prevent disturbing currents which might be generated by the calling party from passing out to the trunk line and so interfering with the operation of the valve receivers connected to both ends of the trunk. Since the stopper valve is a one-way device, it offers no obstruction to signals coming backwardly over the line to the calling end and accordingly, therefore, any tone signals received during the setting up of the connection were received quite freely. When the connection was completely set up and the called party answered, an answer signal was sent backwardly over the trunk to bring about the removal of the stopper valve at the sending end so that conver-

sation could take place in both directions of transmission.

Although the use of a stopper valve provides a good degree of protection against disturbing currents generated at the sending end interfering with the V. F. receivers, its presence in the line is nevertheless undesirable in certain circumstances, particularly in the case of non-metered calls. Generally speaking this type of call is routed through to an operator's position and the terminating apparatus is such that it does not send back an answering signal so that the operator may talk to the calling party and give him the information required without metering the call against him. When, however, such a call is originated over a V. F. trunk including a stopper valve, it is necessary to arrange the terminating apparatus to send back an answer signal in order to bring about the removal of the stopper valve to enable conversation to take place.

As will be appreciated this is particularly undesirable in the case of automatic calls because the answer signal brings about automatic metering of the call against the calling party and it is therefore necessary in such circumstances for the operator to make out a credit slip for such calls in order that they shall be deducted from the calling subscriber's account. From an operating point of view such arrangements are undesirable and it is one of the advantages of the present invention that they have been avoided.

In order to give a good degree of speech immunity for supervisory signals which are transmitted over the trunk after the connection has been set up, it is arranged according to the invention that the apparatus measures such signals as regards their frequency, their duration and their spacing. The sequence is such that it is unlikely to be reproduced fortuitously and there is therefore little likelihood of false operation from disturbing signals.

A further advantageous feature of the invention which is particularly desirable in connection with tandem working is that upon the receipt at one exchange of the common prefix signal which precedes the code signal a blocking device is connected in circuit with the trunk line leading to a following exchange, said blocking device by introducing considerable attenuation into the speaking circuit preventing the code signal from actuating apparatus at said following exchange.

The invention will be better understood from the following description of one method of carrying it into effect, reference being had to the accompanying drawings comprising Figs. 1-9. Of

these drawings, Figs. 1-4 show the circuit arrangements of a sleeve-controlled outgoing relay set, Figs. 5 and 6 show the circuit arrangements of an incoming relay set, Figs. 7 and 8 form a trunking diagram of various combinations of trunk routes to which the invention may be usefully applied while Fig. 9 shows an alternative circuit arrangement including certain modifications which are necessary if the incoming relay set is required to respond to busy flash signals.

Before the detailed circuit operations are described, a description will be given of the general method of working with reference to the trunking diagram, Figs. 7 and 8. In this diagram exchanges A-H are shown interlinked by V. F. and D. C. trunks. Like pieces of apparatus in the various exchanges have been given like designations, for example, MB is manual board, O/G is outgoing relay set, I/C is incoming relay set, VF is voice frequency receiver, A-A RS is auto-to-auto relay set, while VF. TRK and D. C. TRK are voice frequency and direct current inter-exchange trunks respectively.

Assuming that the operator at exchange B plugs into the jack at the manual board MB leading to a free outgoing relay set O/G, her supervisory lamp will flicker and the outgoing relay set will send a 100 milli-seconds (m. s.) X voice frequency pulse forward over the trunk to the incoming relay set I/C at exchange C to bring about the seizure of an associated first selector. The operator now operates the dialling key whereupon the supervisory lamp is extinguished and when she dials the required subscriber's number, the impulses are received and stored on uniselectors in the outgoing relay set. Each train of impulses received at the outgoing relay set is re-transmitted over the trunk in coded form made up of a combination of four voice frequencies, hereinafter referred to as W, X, Y and Z. Each coded digit transmitted is preceded by a preparatory signal comprising all four frequencies, W, X, Y and Z which are effective in the incoming relay set I/C to prepare the voice frequency receiver thereat for operation. The prepare pulse also takes control of any echo suppressors in the route to turn them into the correct direction for transmitting. Conveniently the W, X, Y, Z frequencies used are of 900, 750, 600 and 500 cycles respectively.

The coded digit comprising not more than three of the frequencies W to Z is decoded at the incoming relay set and converted into a marking on the bank of a uniselector which counts the sending out of a corresponding train of loop impulses to set the automatic switches in exchange C. After an interval which is measured in the outgoing relay set and is sufficient to allow for the setting up and hunting time of the automatic switch in exchange C, the second prepare and code signals are transmitted and are dealt with similarly.

When all digits have been dealt with and the switching equipment at exchange C has been set to connect with the required subscriber, the calling operator will receive ringing tone, busy tone, or NU tone to denote the state of the called line.

When the called subscriber answers, repeated Y pulses of 140 m. s. duration spaced 360 m. s. apart are sent back from the incoming relay set in exchange C to bring about the extinguishing of the supervisory lamp in the operator's cord circuit at exchange B. When this is done, an acknowledgment signal is transmitted back from the outgoing relay set comprising a single 440

m. s. pulse of X frequency which serves to terminate the sending of the repeated Y pulses from the incoming relay set. Conversation now takes place and when the called party clears, repeated Y pulses similar to those forming the answer signal are transmitted from the incoming relay set back to the outgoing relay set where they bring about the lighting of the operator's supervisory lamp. When the operator clears in response to the clear signal, the outgoing relay set sends forward to the incoming relay set a clear signal comprising a two-seconds X pulse followed by a 300 m. s. Y pulse which causes the incoming relay set to clear down and release the train of automatic switches at exchange C.

In case the operator has to clear in face of ringing, busy or NU tone, the clear signal under these circumstances is lengthened to a six-seconds X pulse followed by a 300 m. s. Y pulse. The object of the long X pulse is to ensure that the clear signal will get through in face of NU tone which is interrupted at the source for one second after the tone has been transmitted for five seconds.

The proposed voice frequency digit code is as follows:

	Digit	Code	Digit	Code
30	1	W	6	XZ
	2	Z	7	YZ
	3	WX	8	WXY
	4	WY	9	WXZ
	5	WZ	0	WYZ

The proposed voice frequency supervisory signal code is as follows:

	Condition	Signal
40	Seizing pulse	100 m. s. X.
	Coded prepare pulse	160 m. s. WXYZ.
	Coded digit pulse	100 m. s. W to Z.
	Subscriber answer signal	140 m. s. Y.
		360 m. s. space (repeated).
	Acknowledgment signal	440 m. s. X.
	Called subscriber clear signal	140 m. s. Y.
45		360 m. s. space (repeated).
	Operator clear signal	2 seconds X.
	Operator clear on no reply	300 m. s. Y.
		6 seconds X.
		300 m. s. Y.

50 As will be seen from the trunking arrangements of exchange C, the outgoing relay set may be taken into use from any one of three sources, namely, manual board, automatic local subscriber, or incoming relay set from a distant exchange.

55 In the case of seizure from an automatic local subscriber, the operations are substantially similar to those already described for seizure from the manual board, except that resistance battery is connected to the sleeve of the manual board 60 jack to busy the outgoing relay set against seizure from this source.

In case the outgoing relay set in exchange C is taken into use via an incoming relay set in the same exchange, a battery signal over both lines is 65 extended backwardly from the outgoing relay set to the incoming relay set to cause the incoming relay set to switch the lines straight through and cut out of circuit the decoding and retransmitting apparatus. At the same time in the outgoing relay set the lines are extended by way of a repeating coil bridge to the incoming relay set in exchange D and the storing and code sending apparatus in the outgoing relay set of exchange C is cut out of circuit. Code signaling therefore takes 70 place directly from the outgoing relay set of ex-

change B to the incoming relay set of exchange D.

In case the call from exchange C is to be routed over a D. C. trunk to exchange E, access will be had from the incoming selector to the line side of the auto-to-auto relay set A—A RS, thus cutting this relay set out of circuit. This arrangement is desirable to avoid two repetitions of the impulses in the same exchange. The incoming relay set extends earth forwardly to hold the automatic switches in exchange C.

If now the call to exchange E is extended over a VF trunk to exchange G, signals passed between the outgoing relay set in exchange E and the incoming relay set in exchange C bring about the setting up of straight through connections and the disabling of the coding and impulsive apparatus. Signaling therefore takes place directly from the outgoing relay set in exchange B to the incoming relay set in exchange G so that the conditions become similar to the VF to VF case already described.

In case the connection from exchange E is extended over a D. C. trunk to exchange F and then over a VF trunk to exchange H, a different set of conditions arises because an auto-to-auto relay set at exchange E is now interposed in the trunk route. It is therefore now impossible to signal by means of the simplex battery connection between the outgoing relay set of exchange F and the incoming relay set of exchange C to cause these sets to switch over to straight-through connections. On the other hand, unless means are provided to prevent it, the VF signals from the outgoing relay set of exchange B can find a circuit by way of the condenser bridge in the auto-to-auto relay set of exchange E to the incoming relay set of exchange H and this would bring about the generation of two trains of impulses for each train of impulses transmitted from the outgoing relay set in exchange B. To prevent this the incoming relay sets are provided with blocking devices in the line circuit which function almost instantaneously upon reception of the VF prepare signal preceding each code and thus prevent the code signals reaching the incoming relay set at a distant exchange such as exchange H. Thus the sequence of impulsive insofar as setting up of automatic switches in exchange H is concerned is as follows. VF signaling between exchanges B and C; conversion at the incoming relay set of exchange C to D. C. impulses which extend by way of exchange E and the auto-to-auto relay set threat to outgoing relay set of exchange F. Reconversion takes place at exchange F to VF signals which extend to exchange H and are there changed back again to D. C. impulses to set up the automatic switch train in exchange H.

Referring now to the detailed operations involved in setting up a connection over the equipment shown, when the operator plugs into jack JCK, Fig. 1, if the cord circuit speaking key is thrown relay M is operated over the sleeve circuit and in turn operates the relief relay MM, Fig. 4. Relay MM at contacts *mm1*, Fig. 1, connects flicker earth to the upper low resistance winding of relay M to flash the lamp in the operator's circuit to provide an indication that she is connected to a dialling trunk, and at contacts *mm2*, Fig. 4, connects earth to the P conductor incoming from selector levels to guard the relay set against seizure over this path and also operates relay SR. Relay SR at contacts *sr1* causes the switch TS to self-drive from its home position to position 1 where relay CO is operated over the off-normal bank TS1 and relay FXY is operated over bank

TS4. Relay CO at contacts *co3* disconnects relay SR and also at contacts *co1* and *co2*, Fig. 2 removes the line termination resistance TER and connects the trunk line through to the VF signaling circuit via the repeating coil RPC1. In connection with the terminating resistance TER, it should be mentioned that for single-way trunk working the jack points 10 and 11 are strapped together as shown. For bothway trunk working, however, this strapping is removed and the jack points 10 and 12 are cross-connected to the termination in the incoming relay set. Relay FXY in operating, at contacts *fxyl* brings up relay CS and at contacts *fxyl* causes the switch TS to self-drive over its bank TS3 to the third position. During the period that the switch is self-driving over the two strapped contacts, X frequency is applied to transformer VXF via contacts *fc2*, *fxyl* and *aa1* and terminating resistance VTR and then extends via contacts *cs1* and *cs2* and contacts *co1* and *co2* to the trunk line to form a seizing signal to the incoming relay set at the distant exchange. With switch TS in position 3, relay FXY releases to terminate the X pulse after a period of the order of 100 m. s. and at contacts *fxyl* operates relay FC which locks and at contacts *fc3* causes the switch TS to step to position 4 from which it drives to position 6 over bank TS5 and interrupted earth connected to conductor 13. Relay FXY, in releasing, at contacts *fxyl* releases relay CS.

When the operator throws the dialling key, battery is connected to both lines and relay RR, Fig. 1, is operated over its upper winding, while at the same time a high resistance is introduced into the sleeve circuit to extinguish the calling supervisory lamp. Relay RR at contacts *rr1* operates relay A which in turn operates relay B, Fig. 3, to prepare certain impulsive circuits and operate relay BR, Fig. 4. Relay BR at contacts *br1* drops relay RR and at contacts *br1* and *br2* connects relay A to the tip and ring lines extending to the operator's dialling circuit and also at contacts *br3* disconnects the flicker earth circuit and connects up relay KR into the sleeve circuit; this relay however will not operate owing to the high resistance already introduced therein. When the dial is turned off-normal, balanced battery on the lines is replaced by a loop through the dial impulse springs and relay A continues to hold. When the dial is released, relay A responds to the impulses which it repeats at contacts *al*, Fig. 3, via relay C to the driving magnet DSAM of the first digit storing switch DSA so that wipers of this switch are stepped to a corresponding position. Relays B and C hold operated during the impulsive and the latter at contacts *c2*, Fig. 4, operates relay CS to prepare the VF signaling circuit at contacts *cs1* and *cs2*, Fig. 2. Relay C also at contacts *c1*, Fig. 3, energises the driving magnet DDM of the digit distributor switch DD, but as this switch is of the reverse drive type its wipers are not moved at this time.

At the end of the first series of impulses, relay A remains energised and relay C releases after its slow period and at contacts *c1* completes a circuit over bank DSA1, Fig. 3, for operating relays CNA and CNR in series. If the digit dialled is 5 or less, relay CNA operates over its left-hand winding and as a result a short interdigital pause is provided between the retransmitted digits as will appear subsequently. Relay CNR at contacts *cnr2* advances the sending control switch SC from its home position to position 1 where relay ST is operated over its two windings in series. Relay

ST thereupon at contacts *st1* short-circuits its left-hand high resistance winding to self-drive the sending control switch SC to position 4, at contacts *st2*, Fig. 4, maintains relay CS and at contacts *st3*—*st6* causes a prepare pulse of WXYZ frequency to be connected via the transformer VXF to the trunk line to the distant exchange. When the sending control switch SC reaches contact 4, relay ST releases after its slow period thereby disconnecting the WXYZ prepare pulse and at contacts *st1* operates relay S over its two windings in series with magnet SCM. The duration of the prepare pulse is thus measured by the time taken for the switch SC to step from contact 1 to contact 4 plus the slow release period of relay ST which gives a total figure of approximately 160 m.s. Relay S at contacts *s5* holds relay CS and at contacts *s3*, Fig. 2, connects the code pulse to the line, this pulse being dependent for its composition on the setting of the switch DSA as fully described in the previously mentioned specification so that it is thus characteristic of the digit dialled. Relay S also at contact *s1* short-circuits its high resistance left-hand winding to self-drive the switch SC to contact 9 where relay Z operates over its high resistance lower winding and at contacts *s4* disconnects the code pulse from the trunk line. The duration of the code pulse is measured by the time taken for switch SC to self-drive from contact 4 to contact 9 which is approximately 100 m.s. Relay Z holds relays CNA and CNR at contacts *z1* and at contacts *z2* causes the switch DSA to self-drive to its home position where relay Z releases and at contacts *z2* causes the switch SC also to drive to its home position, while at contacts *z3* relay CS is released.

If in the meantime the operator has dialled the second digit on to switch DSB, (not shown) relay CNR will be maintained operated in series with a relay CNB, not shown, and accordingly when the switch SC comes into its home position it will again self-drive to contact 1 where relay ST will re-operate to send out the prepare pulse of WXYZ frequency followed by the code pulse which is picked up from the setting of the wipers of the switch DSB which is assumed to be similar to the switch DSA already described.

It should be explained here that if, as has been assumed, the digit dialled was 5, the interdigital pause provided between the two code digits transmitted to line will be measured by 20 self-driving steps of the switch DSA, say 400 m.s., plus 16 self-driving steps of switch SC, say 320 m.s. giving a total of 720 m.s. approximately. During this period five machine-generated pulses are delivered at the distant exchange to the incoming selector after which hunting must take place to select an idle trunk in the level selected. While the selector is hunting, the incoming decoding relays are released to receive the second prepare and code signals which will require a time period of 160 plus 100 m.s. giving a total of 260 m.s. which may be added to the 720 m.s. already mentioned to give a total of approximately 980 m.s. for the complete interdigital pause during which the incoming selector must be set to the required level and perform its hunting operation.

If, however, the first digit dialled had been 6 to 0, a longer interdigital pause would be required to enable the incoming selector to perform its sequence of operations and this is derived as follows. Relay CNA under these conditions would be operated over its right-hand winding in series with relay CNR so that when relay S operated,

relay EP would operate and lock to earth over bank and wiper DSA1. Accordingly, when the switch DSA reaches its home position, thus measuring off part of the interdigital pause, relay EP will hold during the slow period due to its short-circuited upper winding and at contacts *ep2* will cause the switch DSA to make another revolution. During this revolution relay EP releases but relay Z holds to bring about a substantial increase in the interdigital pause. For example, if the digit 0 had been dialled, the interdigital pause would be made up as follows: fourteen steps of the switch DSA plus an additional revolution making 39 steps in all gives a period of approximately 780 m.s. To this must be added sixteen steps of the switch SC say 320 m.s. plus a further 260 m.s. representing the transmission time of the prepare and code pulses of the second digit giving a total interdigital pause of approximately 1,360 m.s. The object of this extra pause period is to ensure that the distant selector has sufficient time to perform its level-selecting function plus its trunk-hunting function before the next decoded digit is transmitted to the succeeding switch.

When all stored digits have been transmitted in code, relay CNR finally releases and at contacts *cnr2* opens the kick-on circuit for the sending control switch SC, while at contacts *cnr1*, Fig. 4, it brings up relay BS, Fig. 2, which has no function at this stage.

Although four digit storing switches DSA—DSD have been provided, it is possible that in practice a lesser number may be found satisfactory depending upon the speed at which storing and retransmitting in code can be accomplished and upon the number of digits to be dialled. As shown the digit storing switches DSA—DSD are taken into use in cyclic repetition, that is to say, when the fourth digit has been stored on the switch DSD, the switch DSA which will by this time be normal is again taken into use to store the fifth digit and so the storage cycle repeats itself. With the CNA—CND digit storing circuit shown in Fig. 3, however, it is possible that if the fifth digit dialled is received before all the first four digits have been sent out in coded V. F. form, the DSA switch, on which the fifth digit is received, will take precedence and so will upset the cyclic function. This trouble may be simply overcome by providing, in the CNR relay individual battery feeding circuits to the three relays CNA—CNC, break contacts of relay CND which are paralleled by make contacts of each relay concerned. As regards relay CND this will remain directly connected to relay CNR as shown in Fig. 3. With these arrangements the operation in turn of the relays CNA—CNC is not interfered with and on operating they will lock independently of relay CND, but as soon as relay CND is operated in response to the fourth digit, none of the preceding relays can be operated in response to a fifth and subsequent digits. This condition obtains until the fourth digit has been sent out in coded V. F. form after which the battery feeding circuits of the three relays CNA—CNC are recompleted. If by this time the fifth digit has been dialled, the DSA switch will have been already set accordingly and relay CNA will now re-operate to provide for the sending out of this digit. Similar remarks would apply to the sixth and seventh digits, while the eighth digit would function on relay CND in the same manner as for the fourth digit. By this means it is contemplated that up to ten digits could be safely handled by the four digit switches DSA—DSD.

When the operator restores her dialling key at the end of dialling, the current in the sleeve circuit is increased and the battery applied to the tip and ring conductors is removed shortly afterwards. Relay KR, Fig. 1, thereupon operates and locks up at contacts *kr1* while at contact *kr2* it releases relay A. Relays B and BR in turn restore after their slow periods and the former at contacts *br3* advances the digit distributor switch DD to its mid position preparatory to the operation of relay AA at a later period. Relay BR at contacts *br3* connects the earthed low resistance lower winding of relay RR into the sleeve circuit and though relay RR receives insufficient current to operate the supervisory lamp again glows under this condition. Relays M, MM, KR, CO, FC and BS remain operated and the line condition is now such that the operator may listen to tones and if necessary speak without the necessity for a called party answer signal, but no supervision is given.

If the operator restores her cord circuit speaking key the sleeve circuit current is increased to a value sufficient to operate relay RR and this relay at contacts *rr2*, Fig. 1, maintains a suitable V. F. termination on the trunk line, in place of the operator's telephone set.

When the called party answers, the incoming relay set at the distant exchange transmits 140 m. s. of Y frequency over the trunk followed by a space period of 360 m. s. and this signal is repeated until acknowledged by the transmission of an X signal from the outgoing relay set. Upon the reception of the Y frequency, relay Y operates in the YF receiver VFR shown schematically as a dotted rectangle in Fig. 2 and opens the circuit to relay BS which releases after a slow period of 80-110 m. s. To release relay BS therefore the Y frequency must be applied for a sufficient period and when relay BS has released, relays MS and MT are operated in turn and hold for the remainder of the Y pulse. When the Y pulse is finished, relay BS re-operates and at contacts *bs1* opens the circuit for relay MS which has a release time of 300-400 m. s. Relay MT has a release time of 200-300 m. s. If the break period is of the correct duration, namely 360 m. s., then this period plus the 80-110 m. s. release time of relay BS, which releases in response to the next Y pulse, will be sufficient to cause relay MS to release but not relay MT. Hence on the reception of the next Y pulse the "subscriber answer" relay SA will be operated over contacts *sy2*, *sz1*, *sb2*, *ms1*, *mt1*, *sy1*, *bs1*, *ac5*, *y1* and *en1* to earth. At the end of the Y pulse, or when relay MT releases, relay SB which has been short-circuited hitherto operates in series with relay SA and locks. Relay SB operates relay AA, Fig. 3, in the self-driving circuit of the switch DD and relay AA at contacts *aa2*, Fig. 4, reoperates relay CS and at contacts *aa1*, Fig. 2, applies an X pulse acknowledgment signal to the outgoing trunk. The duration of this acknowledgment signal is measured by twelve steps of the switch DD plus the release time of the relay AA which releases when the DD switch reaches the home position and which in turn releases relay CS. When the X pulse is received at the distant incoming relay set, the transmission of the Y pulses ceases and relay BS remains operated.

It should be mentioned that relay SA at contacts *sa3*, Fig. 1, connects battery via resistances YP and YQ to the ring of the jack for through supervision and also at contacts *sa6*, Fig. 1, removes the short-circuit by way of the lower wind-

ing of relay RR from the high resistance winding of relay M so as to dim the supervisory lamp in the operator's circuit. If relay RR has been held operated up to this time on its lower winding, it now releases.

Conversation now proceeds, and when the called party clears, the incoming relay set at the distant exchange transmits Y pulses of the same type as for the called party answer signal. At the outgoing end relays M, MM, KR, CO, FC, BS, SA and SB are held operated and the switch TS is in position 6. Accordingly the first 140 m. s. pulse of Y frequency releases relay BS and operates relays MS and MT as already described. During the following 360 m. s. break period relay BS is operated and releases relay MS but not relay MT so that when the next Y pulse is received and relay BS again releases, during the slow release period of relay MT relay SY operates over contacts *sy2* and at contacts *sy1* completes a locking circuit for itself for the remainder of the Y pulse. Relay SY also at contact *sy3* operates relay SZ and at contacts *sy2* releases relay SA which at contacts *sa3*, Fig. 1, disconnects battery from the ring of the jack for backward supervision, and at contacts *sa6* restores earth via the low resistance winding of relay RR to the jack sleeve circuit to re-light the operator's calling supervisory lamp.

As long as the Y pulses persist, relay SY remains held because its release time is 400-450 m. s., i. e. longer than the 360 m. s. break period and consequently if the called subscriber should again remove his receiver, the Y pulses will cease and after its slow period relay SY releases and disconnects relay SZ. During the slow release period of relay SZ relay SA re-operates and locks in series with relay SB to restore the speaking conditions.

When the operator clears by removing the plug from the jack in response to the clear signal, relays M and MM in the sleeve circuit release and the latter releases relay KR. The release of relay MM at contacts *mm2*, Fig. 4, steps the switch TS from position 6 to position 7 by way of bank TS3, whereupon relay BR operates in series with relay SR over bank TS4. Relay SR on operating at contacts *sr3* re-operates relay CS and these relays together bring about the application of an X frequency pulse forwardly over the trunk by way of contacts *sr2*, *cs1* and *cs2*. Since relay SB is operated, the switch TS continues to self-drive from position 7 to position 15 via bank TS3 and contacts *sb4* and then steps by means of interrupted earth on lead 13 from position 15 to position 19 via bank TS5. Relay FXY is then operated over bank TS4, contact 19, and serves to disconnect the X frequency at contacts *fxy1*, Fig. 2, after a period of application of two seconds and at the same contacts to connect up Y frequency to the trunk. When the wiper leaves position 18 of bank TS4, relays SR and BR are caused to release after their slow periods and on the release of the latter, earth is extended over bank TS3 to step the switch to position 20. Relay FXY then releases after its slow period and thus terminates the Y signal after a period of application of 300 m. s. and also releases relay CS. Switch TS then steps from position 20 to position 23 via bank TS3 and contacts *ac1*, and then slow steps from earth on lead 13 over contacts 23 and 24 via bank TS5 to reach its home position where relays CO, FC and SB release. During the forward application of Y frequency relay BS will have released and at the end of the signal relays

SY and SZ release in turn. Relay CO disconnects the busy condition from the sleeve of the jack at contacts *co5*, Fig. 1, and as earth is also removed from the P conductor leading to the selector levels when the TS switch reaches its home position the relay set is free for further use.

Consideration must now be given to the condition when the operator clears before receiving the answering signal or in face of any tone (ringing, busy or NU) or on a non-metered call. Any of these conditions are characterised by the non-operated condition of relay SB so that when the operator withdraws the plug and releases relays M and MM, the switch TS is caused to slow step from position 7 to position 19 by way of interrupted earth supplied over lead 13. Accordingly, therefore, the X pulse which precedes the Y pulse is lengthened from 2 to 6 seconds, after which it is followed by the normal 300 m. s. Y pulse. The object of the long X pulse under these conditions is to ensure that the clear signal will be received at the distant incoming end when, for example, NU tone is being transmitted backwardly. The NU tone is transmitted for five seconds and disconnected for one second and this arrangement ensures that the clear signal which is being extended forwardly shall be able to break in and register at the incoming relay set.

When the outgoing relay set is taken into use over the negative, positive and P trunks extending from selector levels, the call may have been originated either by a subscriber on the same exchange or via an incoming V. F. relay set from a distant exchange, say B. In the first case the subscriber's dialled impulses are converted by the switches DSA—DSD into VF prepare and code pulses, while in the second case, where through working is required, the outgoing relay set merely transmits the X seizing signal to the distant incoming VF relay set after which further prepare and code pulses are transmitted directly through the outgoing relay set to the distant incoming VF relay set without modification.

In the case when the outgoing relay set is taken into use from a subscriber in the same exchange, earth extended forward over the private conductor P operates relay SR, Fig. 4, which causes the switch TS to self-drive over bank TS3 to the first position where it operates relays CO, CS and FXY. Relay CO operates relay BS and drops relay SR, while relay FXY extends a 100 m. s. X seizing pulse forwardly over the trunk to the distant incoming relay set. Relay FXY also causes switch TS to self-drive to position 3 where relay FXY is disconnected and after its slow period releases to terminate the X pulse. Relay FC is then operated and locks up and serves to step TS to position 4 from which it slow steps from interrupted earth on conductor 13 to position 6. Relay FC also brings about the operation of relay A, Fig. 1, over the calling subscriber's loop and relay A in turn brings up relays B and BR to prepare the circuit for the reception of the dialled impulses. From this point the call proceeds as for an operator call already described, that is to say, relay A responds to the dialled impulses which are stored via the digit distributor switch DD on the coding switches DSA—DSD. Subsequently under the control of the sending switch SC the coded digits are transmitted to line in the form of prepare and code pulses and are received on decoding apparatus at the incoming relay set in the distant exchange. Relay CO under these conditions busies the manual board jack by connecting resistance battery to the sleeve cir-

cuit. When the called party answer signal is received in the form of repeated 140 m. s. Y pulses as already described, relays MS and MT check the length and spacing of the pulses and if these are correct allow relays SA and SB to operate. Relay SA at contacts *sa4* and *sa5*, Fig. 1, reverses the A relay connections towards the calling party for supervision, while relay SB operates relay AA to cause an X pulse acknowledgment signal to be transmitted forwardly to the distant exchange. This signal lasts for a period measured by the homing time of the switch DD via the low resistance relay AA plus the slow release period of relay AA which is disconnected when switch DD arrives at its home position. The reception of the X pulse acknowledgment signal at the distant exchange causes the backward Y answer signal to be disconnected and conversation may now take place.

In the case of a call via selector levels from an incoming VF relay set, earth is connected to both the negative and positive lines and serves to operate relay AC, Fig. 1, while the normal forward earth on the P conductor operates relay SR. Relay AC at contacts *ac2* and *ac3* connects the negative and positive lines from the selector level through to the outgoing trunk line while relay SR steps switch TS from the home position to contact 1 where relays CO, CS and FXY are operated. Relay CO operates BS, drops SR and disconnects the trunk line termination TER. Relay FXY extends a 100 m. s. X seizing pulse forward over the trunk to the distant exchange and steps the switch TS to contact 3. In this position relay FXY is disconnected and when it releases after its slow period the X seizing pulse is terminated. Since relay AC is operated, switch TS self-drives to position 20 via bank TS2 and remains there until the end of the call so that as it leaves position 4 while relay FXY is still operated, relay FC is not operated. The incoming VF prepare and code pulses are thus extended directly through the outgoing relay set to the distant exchange. Relay CO busies the jack by connecting battery to the sleeve circuit, while switch TS at bank TS4 holds earth on the P wire to busy the outgoing relay set against seizure over the selector levels. When the connection is set up and the called party answers, repeated Y pulses are extended from the distant exchange directly through the outgoing relay set and are acknowledged by a 440 m. s. X acknowledgment signal extending from the calling end of the connection directly through the outgoing relay set. It will be noticed that the Y relay of the VF receiver VFR is operated from the Y pulse but as relay AC is operated at this time the response of relays MS, MT, SA and SB is prevented by contacts *ac5*, Fig. 2. When the calling end of the connection is cleared, earth is removed from the negative and positive lines thus releasing relay AC which allows switch TS to self-drive over contacts 20—23 via bank TS3 after which it slow steps to its home position.

If the operator inadvertently withdraws the plug while the called party is still connected and possibly is speaking at this time, switch TS will run home from position 6 to extend the clear signal of two seconds X followed by 300 m. s. Y and release the equipment in the outgoing relay set. If however the called party is still talking at this time, any echo suppressor in the connection will be held against the clearing signal which may therefore fail to get through to the distant end of the connection. It is therefore

necessary when the called party finally clears to arrange for the switch TS to perform another revolution in order that the clearing signal may be sent forward to the distant end of the connection. Accordingly, therefore, when the called party replaces his receiver, Y pulses are transmitted backwardly over the connection, these comprising as usual 140 m. s. of Y frequency followed by 360 m. s. space period. The first Y pulse operates relays MS and MT and during the first 360 m. s. break period relay MS releases so that at the commencement of the next 140 m. s. Y pulse relay SA is operated and at contacts *sa2*, Fig. 4, causes the switch TS to step from its home position to contact 1. Relay SB is operated and locked when the Y pulse is finished and from then on the switch TS makes a complete revolution during which the clearing signal comprising a two-second X pulse followed by a 300 m. s. Y pulse is transmitted to the trunk line to release the distant equipment. It should be mentioned that during the revolution of the switch TS the X seizing pulse is again transmitted while the switch is passing over the early contacts of the bank, but under these circumstances this signal produces no switching function at the distant exchange.

Referring now to the circuit changes produced at the incoming relay set, Figs. 5 and 6, when the 100 m. s. X seizing pulse is received over the trunk line from the outgoing relay set, relay *IX*, not shown but assumed to be located in the valve receiver *IVFR*, operates and in turn brings up the relief relay *XR*. Relay *XR* at contacts *xr3* operates relay *K* which locks up at contacts *k1*, at contacts *k2* operates relay *PY*, Fig. 6, and at contacts *k4* extends earth forwardly over the P conductor to the incoming selector to busy this switch. At the end of the X seizing pulse, relay *IX* in the valve receiver releases and in turn drops relay *XR* which at contacts *xr4* operates relay *NN*. Relay *NN* at contacts *nn6* further earths the P conductor extending to the incoming selector, at contacts *nn1* operates relay *KK* over the negative line in series with one winding of the A relay in the incoming selector and at contacts *nn3* operates relay *GX*, Fig. 5. Relay *GX* at contacts *gx4*, Fig. 6, connects battery by way of a high resistance *YF* to the centre point of the repeating coil which finds a circuit to earth at the centre point of the transformer which connects the valve receiver *IVFR* to line. A small current is thus caused to flow by way of various relay contacts connecting with the line circuit which are thus "wetted" to prevent coherer trouble. No further operations take place at this stage and the incoming selector is now ready to receive the train of impulses.

When the outgoing relay set transmits the 160 m. s. prepare pulse of *WXYZ* frequency as already described, relays *IW*, *IX*, *IY* and *IZ* operate in the V. F. receiver and in turn bring up their relief relays *WR*, *XR*, *YR* and *ZR*. Over the series connected contacts *xr4*, *yr4*, *zr3* and *wr3* relay *CA* is now operated, whereupon the bothway line termination comprising resistances *YB*, *YC*, *YJ*, *YD* and *YE* and condenser *QA* which normally imposes a loss of the order of 3 db, is converted into a combined line termination and infinite attenuation loss pad which prevents the passage of signals so that the line is blocked at this point. The purpose of this arrangement will be described later in connection with tandem calls.

The prepare pulse, as already described, has

a duration of approximately 160 m. s. and is followed immediately by the code pulse which comprises frequencies *W*, *X*, *Y* and *Z* in suitable combinations having a duration of 100 m. s. In the example in question the digit 5 comprising the frequencies *W* and *Z* is assumed to have been transmitted so that relays *IX* and *IY* are released and in turn drop their relief relays *XR* and *YR*. The short-circuit is thus removed from relay *CB* which immediately operates from the earthed contacts *nn2* in series with relay *CA*, and at contacts *cb4* and *cb1* locks relays *WR* and *ZR* corresponding to the code which has been transmitted. Relays *WR* to *ZR* have a pyramid chain of contacts (not shown) connected to the bank *SS2* of the sender switch *SS*, and since the code relays *WR* and *ZR* are operated at this time, earth is connected to the sixth contact of the bank *SS2* in order to terminate the sending after five impulses have been transmitted to the incoming selector as will appear subsequently. Relay *CB* also at contacts *cb5* releases relay *GX* and operates relays *PC* and *P*, the latter locking over its own contacts. Relay *PC* at contacts *pc1* operates relay *CC* which at contacts *cc1* prepares a circuit for relay *IG* which operates when the constantly driven impulse springs *66%M* next open. Relay *IG* at contacts *ig2* drops relay *KK* and at contacts *ig1* extends the impulse springs *66%M* to the driving magnet *SSM* of the sender switch. Relay *IG* also at contacts *ig2* transfers the forward holding loop extending to the selector to the impulse springs *33%M* which are closed at this time, since they are out of phase with the magnet impulse springs *66%M* which have just opened to bring about the operation of relay *IG*. Accordingly, the sending switch *SS* now steps its wipers until they encounter the marking earth connected to the sixth contact of bank *SS2* over contacts of the coding relays *WR* and *ZR*, while at the same time the impulse springs *33%M* transmit five impulses to the incoming selector as described in the previously mentioned specification. Relay *SZ* operates when wiper *SS2* comes into its sixth position and locks over contacts *sz1* to the homing bank *SS1*. Relay *SZ* also at contacts *sz2* short-circuits the *33%M* springs to terminate the impulses to the selector and at contacts *sz3* releases relays *CA* and *CB* which have been held in series. Relay *CB* at contacts *cb6* drops relay *IG* which at contacts *ig4* causes the sending switch *SS* to home, while the holding circuit for the selector is again transferred to relay *KK* which re-operates. Relay *CB* also re-operates relay *GX* and releases relays *WR* and *ZR* as well as relay *PC* after its slow period which is followed by the release of relay *CC* also after its slow period. Relays *K*, *PY*, *NN*, *KK*, *GX* and *P* remain held.

After a pause long enough to permit the incoming selector to hunt over the selected level, which pause is determined in the outgoing relay set as already described, the next prepare and code pulse is transmitted and the operation is repeated until all the impulse trains have been transmitted. It will be appreciated that the prepare pulse of *WXYZ* frequency ensures that any echo suppressors in the connection are switched into the correct direction and provides a test that all the responding relays in the incoming V. F. receiver are operating satisfactorily. If this is not so it will be impossible for a complete connection to be set up and there is no danger of 75 connection being made to the wrong party.

The connection is thus fully set up and the called party is rung. When the called party answers, battery is reversed over the forward trunk so that relay KK releases and relay EE operates. Relay EE at contacts *ee2* brings up relay IR which at contacts *ir2*—*ir4* alters the connection to the loss-pad to render it ineffective and at contacts *ir1* drops relay K. Relay K opens the circuit of relay PY and during the slow release period of the latter, relay MA is operated and locks up over contacts *ma1* and *gx1*. Relay MA at contacts *ma3* and *ma4*, Fig. 5, connects up the secondary winding of the transformer VSF to the backward trunk and at contacts *ma2* connects relay FY, Fig. 6, to conductor 14 which extends to interrupted earth having a periodicity of 140 m. s. on and 360 m. s. off. Relay FY therefore pulses to the interrupted earth and extends backward over the trunk repeated 140 m. s. Y pulses with 360 m. s. spacing.

When this signal has been accepted at the outgoing relay set, the latter returns a 440 m. s. X pulse acknowledgment signal which operates relay *IX* in the valve receiver and in turn the relief relay XR. Relay XR at contacts *xr3* opens the circuit of relay GX and operates relay GY. Relay GX releases after its slow period and at contacts *gx1* drops relay MA which connects the line through for conversation and disconnects the repeated Y signal. Relay GY in operating cuts the earth pulse connection to relay FY. Since the repeated Y signal is measured at the outgoing relay set both for length and spacing, it will be appreciated that this gives the desired degree of immunity against false Y signals which may be generated by speech or line noise. Similarly, the X acknowledgment signal is measured against the release time of relay GX (300–400 m. s.) to provide the required degree of immunity against spurious X frequencies on the line. At the conclusion of the acknowledgment signal, relay XR releases, relay GX re-operates and relay GY releases.

When the called party clears, battery is again reversed over the forward line circuit so that relay KK re-operates and relay EE releases. Relay EE at contacts *ee2* drops relay IR to re-introduce the line termination and also operates relay MA. Relay MA connects interrupted earth to relay FY which pulses to send back to the outgoing relay set the clear signal comprising 140 m. s. Y pulses with 360 m. s. spacing. As already explained, in the outgoing relay set this signal results in the release of relay SA which disconnects battery from the ring of the outgoing jack and lights the calling supervisory lamp at the operator's position. Relays NN, KK, GX, P and MA remain held, while relay FY is slowly pulsing.

When the operator clears, the outgoing relay set sends a clear signal comprising a two-seconds X pulse followed by a 300 m. s. Y pulse. The X pulse operates relays *IX*, XR and GY in the incoming relay set and the latter opens the circuit for relay FY to terminate the transmission of the called party clear signal. Relay XR also opens the circuit of relay GX sufficiently long for it to release whereupon it drops relay MA and operates relay CC over contacts *gx3*. When the X pulse is finished, relays *IX*, XR and GY release and relay CC commences to release slowly. The 300 m. s. Y pulse now follows and serves to operate relays *Y*, *YR* and *CR*. Relay CR locks to the earthed contacts *p2* and transfers the holding circuit for relay NN to the Y pulse and also connects earth to the P conductor extending for-

wardly to the automatic switches. When the Y pulse is finished, relay NN releases and drops relays P and KK which open the holding circuit for relay CR. The forward holding loop is opened and the earth on the P conductor is removed on the release of relays NN and CR thus initiating the release of the operated automatic switches, and the incoming relay set is now free for further use.

In regard to tones which may be encountered during the setting up of the call such as ringing, busy and NU, these are passed back along the trunk line in the normal manner except that the line termination which is in circuit under these conditions imposes a 3 db loss but this does not seriously reduce the tone level. The NU tone is broken at the source for one second in every six to allow the release signal to obtain control and thus get through to its destination. As explained above if the release signal is sent before the called party has answered, it comprises 6 seconds of X frequency followed by 300 m. s. of Y frequency. This long signal insures a certain break-in during the 1 second silent period of the NU tone.

Considering now the operation of the incoming relay set under these conditions, since the called party has not answered, relay K will still be operated and hence the X signal operates relay PC which brings up relay CC and from this point the release procedure is identical with that previously described for the normal operator clear.

In case the incoming selector switches through to a short-circuited trunk, arrangements have to be made to prevent this short-circuit masking the VF receiver and so preventing the incoming relay set from accepting the release signal of 6 seconds X followed by 300 m. s. Y. In the face of a short-circuit from the selector, neither of relays KK and EE is operated so that on the release of relays CB, PC and CC in turn relay SC operates over contacts *nns*, *pc1*, *cc3*, *kk1*, *ee1* and *p4* and locks up at contacts *sc1*. At contacts *sc2* and *sc3*, Fig. 6, relay SC disconnects the forward trunk leading to the short-circuit and under these conditions the line termination is maintained since relay IR is not operated and the clearing signals can be satisfactorily received from the outgoing relay set.

In the case of tandem calls over two VF trunks in series, for instance from exchange B to exchange D, Figs. 7 and 8, the following operations take place. The digits dialled cause the selector to seize an outgoing relay set to another VF channel so that battery is returned from the AC relay in this outgoing relay set over the negative and positive lines to operate both relays EE and KK. Relay EE operates relay IR as already described in connection with the called subscriber answer condition, and relay IR releases relay K. As relay KK is also operated at this time, however, relay PY is held operated and no circuit is completed to operate relay MA and initiate the sending of the repeated Y answer signal backwardly over the trunk. With relay IR operated the loss pad and line termination are removed at contacts *ir2*—*ir4* while any circuit for relay CB is disconnected at contacts *ir5* so that the following VF signals pass directly through the incoming relay set without any conversion or repetition. Under these conditions before the incoming relay set can be released, it must receive a long X pulse to drop relay GX followed at the proper interval by a short Y pulse to operate

relay CR. The X portions of the subsequent prepare and code pulses although picked up by the VF receiver in the incoming relay set are not long enough to bring about the release of relay GX. Furthermore, the 440 m. s. X pulse acknowledgement signal which is sent from the originating end in response to the called party answer signal will bring about the release of relay GX, but as this is not followed by a Y signal the temporary release of relay GX brings about no material change in the condition of the incoming relay set. When the release signal comprising a long X pulse followed by a short Y pulse is received, the incoming relay set releases as already described.

In the case of tandem calls over VF and D. C. trunks in series, for instance from exchange B to exchange E, when the D. C. outlet is seized in the second exchange (C), access is had to the outgoing side of the normal auto-to-auto repeater A—A RS, Fig. 7, which is thus cut out of circuit in order to avoid two impulse repetitions in the same exchange. The incoming relay set therefore extends earth forwardly over the P conductor to hold the selector train in the second exchange (C) and also accepts code signals and transmits forward loop impulses to set up the automatic switch train at the third exchange (E). When the called party connected to the third exchange answers, battery is reversed over the line to operate relay EE in the incoming relay set at the second exchange (C) which thereupon sends repeated Y pulses back to the first exchange (B) as already described. The further operation and release of the incoming relay set are as already described.

In the case of tandem calls over VF, D. C. and VF trunks in series for instance from exchange B to exchange G, when connection is made with the outgoing relay set in the third exchange (E), battery over both lines is extended backwardly over the trunk to operate relays KK and EE in the incoming relay set at the second exchange (C) which thereupon cuts out its repeating apparatus and provides a straight-through pair of trunks as already described. Accordingly, VF signals from the outgoing relay set in the first exchange (B) now pass directly without repetition to the incoming relay set at the fourth exchange (G) which converts them to D. C. impulses for setting up the train of switches at this exchange to establish connection with the wanted subscriber. The connection therefore becomes in effect VF to VF since there is no auto-to-auto repeater in circuit at the second exchange (C) and the switches here are held forwardly from the incoming relay set at this exchange.

In the case of tandem calls over VF, D. C., D. C. and VF trunks in series, for instance from exchange B to exchange H, a different set of conditions arises in that an auto-to-auto repeater will be taken into use at the third exchange (E) which prevents battery on both lines from the outgoing relay set in the fourth exchange (F) finding a circuit back to the incoming relay set in the second exchange (C) to cause this to provide a straight through pair of lines as was the case in the VF—D. C.—VF connection. In the absence of any means to prevent it therefore, there is a danger that the V. F. code signals from the originating exchange may be received both at the incoming relay set in the second exchange (C) and the incoming relay set in the fifth exchange (H) and this would result in two trains of impulses being delivered for each digit. This explains the

necessity for the provision of the infinite attenuation loss pad in the incoming relay set.

Considering now the circuit operations, it will be remembered that when the VF prepare impulse is received at the incoming relay set at the second exchange (C), relay CA operates almost immediately and provides an infinite attenuation loss pad which in effect short-circuits the trunk across a resistance bridge to prevent the passage of V. F. signals beyond the incoming relay set. However, during the operate time of relay CA at the incoming relay set in the second exchange (C), relay CA in the incoming relay set at the fifth exchange (H) may operate but will at once release when the CA relay at the first incoming relay set has operated and inserted the loss pad in the trunk. It will be recalled that relays CA and CB lock in series during the reception of the code pulse and while the loop impulses are being transmitted so that neither the prepare nor the code VF signals are transmitted to the incoming relay set in the fifth exchange.

It will be appreciated that the desired blocking effected could also be obtained by breaking the connection between the incoming and outgoing sides of the incoming relay set. The arrangement according to the invention whereby considerable attenuation is introduced is preferable however particularly when combined with the line termination as it involves fewer relay contacts and also it has the advantage that trouble due to dirty contacts would not put the circuit out of action but at the worst would introduce a loss of the order of 3 db.

In the case of non-metered calls which are usually of the enquiry type such as service, interception, enquiry or speaking to B operators at manual exchanges, it will be appreciated that with the circuit arrangements as described conversation can take place immediately without the extension of an answer signal and therefore the automatic metering of non-metered calls is avoided. It will be seen that a 3 db loss pad remains in the connection under these conditions owing to the absence of any battery reversal which would operate relays EE and IR but this does not unduly interfere with speech and furthermore if more than one incoming relay set is included in the connection the loss pad is removed in all incoming relay sets except the one in the terminating exchange where no battery is returned over the negative and positive lines to effect the removal of the pad, and consequently the overall extra loss never exceeds 3 db on this type of call.

Referring now to Fig. 9, this shows the modifications necessary to the incoming relay set to adapt it to function correctly if busy flash signals in addition to the normal busy tone are encountered. For this purpose an additional relay TH is provided and the connections to the line termination and loss pad are suitably modified. On through calls when the incoming relay set is required to provide a straight through connection and disable its repeating apparatus, relays KK and EE operate as before from battery on both lines through relay AC in the outgoing relay set, and as this battery is now made positive instead of negative, relay TH is operated via the metal rectifier MRA and locks up. Relay IR is also operated from relay EE and with all four relays operated the line termination and loss pad is disabled and a straight through connection is provided.

In other circumstances where the incoming

relay set is the terminating one in the connection, relay KK will be operated while the call is being set up. If a busy line is encountered, busy tone is returned as explained and if this is accompanied by busy flash battery on the positive line relay EE is also operated. Since however, relay TH is not operated under these conditions since the battery in question is a negative battery, relay IR in operating does not disable the line termination and loss pad, so that balanced conditions are maintained to the line amplifier which is prevented from "singing" during the busy flash condition.

What we claim as new and desire to secure by Letters Patent is:

1. In a telephone system wherein a connection is established to a called station by automatic switches controlled over a voice frequency signaling trunk including means responsive to a disconnect at the calling end to transmit a forward signal to release said switches, a source of impulses comprising alternating current of determined voice frequency interrupted at predetermined intervals accessible to the called end of said trunk, means in said trunk responsive to a disconnect at the called station to connect said source of impulses to the trunk as a clearing signal whereby the calling station disconnects and the forward signal is transmitted, and means responsive to said forward signal to disconnect the clearing signals from the trunk before the said switch release is initiated.

2. In a telephone system wherein a connection is extended over a trunk in which the functional operations including supervisory and releasing for said connection are controlled by signals from a plurality of sources of alternating currents of different frequencies, means in said connection to transmit impulses of said currents of determined frequency duration and spacing over said trunk in accordance with said functional operations controlled therover, a signal comprising impulses one of said frequencies repeated at a determined rate to control the supervisory functional operation, a second signal comprising another frequency of determined duration, means in said trunk to transmit said second signal to stop said supervisory signal and means in said connection to transmit a subsequent pulse of said first signal within a determined spacing after said stoppage signal is effective to control the functional operation of releasing said connection.

3. In a telephone system, a connection including a trunk line over which voice frequency signals are transmitted to establish a connection and in which a clearing signal of voice frequency is normally sent to the calling end when the called station hangs up and a release signal of voice frequency is then transmitted from the calling end to release the connection, the provision of means responsive to a release signal transmitted from the calling end before a clearing signal is received for causing the transmission of the clearing signal to act as a release signal to release the connection.

4. In a telephone system, a plurality of voice frequency responsive equipments each associated with a trunk line and each normally responsive to received voice frequency coded signals to translate the same into direct current impulses to op-

erate automatic switches to extend a connection, means in each equipment operated only in case a second trunk is seized having such equipment therein in a tandem connection for preventing the translation of received voice frequency signals in the first equipment and causing the transmission of the received signals to the second seized trunk without translation, said means responsive only to a flow of current over the two speaking conductors in parallel.

5. In a telephone system, a trunk line, means for transmitting over said line a plurality of coded signals each comprising impulses of a plurality of different voice frequency sources and a varying number of said frequencies in accordance with received signals and other control signals of varying number of impulses of determined frequency duration and spacing in accordance with other received signals, a plurality of receivers connected successively to said line and responsive to a received signal for translating it to a signal corresponding to said received signal, a blocking means controlled from each of said receivers to prevent the further passage of said received signal current over said line to the successively connected receivers, means in each receiver effective on certain of said coded signals for translating said signal and operating said blocking device to prevent said other receivers from effectively completing said particular code translation and means in each receiver responsive to other received signals to complete the corresponding translation without operating said blocking means.

6. In a telephone system, a trunk line including voice frequency responsive equipment, means for extending a connection thereto and for transmitting coded digit signals of voice frequency currents thereto to extend a connection therover and for transmitting other coded voice frequency signals thereto, a blocking device in said trunk, each digit signal including a portion effective to include the blocking device in the trunk to block further progress of voice frequencies over the connection, and each other signal passing over the connection without blocking.

7. In a telephone system, a voice frequency signaling trunk terminated on a responsive repeater including means for transmitting and receiving over said trunk a signal to seize said repeater and another signal to release said repeater, a switch operating line controlled from said repeater, means responsive to the seizure of the repeater to connect said line to said trunk, said repeater responsive to other voice frequency signals received over the trunk to control a connection, and to repeat said release signal therover, holding equipment in said repeater controlled over said connected line to prevent a false release of said trunk before said line is disconnected, means effective in the event of a short circuit on said line whereby said holding equipment and said other signals are disabled, means in said repeater effective only when said equipment is disabled to disconnect said line from said trunk to permit said release signal to be effective to release said repeater.
